LLOYD W. MOULTON, OF SYRACUSE, NEW YORK, ASSIGNOR TO GAYLORD BROTHERS, INC., OF SYRACUSE, NEW YORK, A CORPORATION OF NEW YORK

TYPE CARD FOR PRINTING MACHINES

Application filed September 23, 1929. Serial No. 394,530.

This invention relates to a type-card adapted to be used in connection with a suitable printing machine, such for example as that shown in my pending application Serial No. 5 394,531, filed September 23, 1929, for printing or otherwise impressing identification characters upon other cards or sheets used in public libraries and other places where books and other articles are loaned to patrons for limited time periods.

In the present practice in most of the well regulated public circulating libraries at least two records are kept on separate cards for receiving the identification characters of the 15 borrower and the date of beginning or expiration of the time period for which the book or other article is loaned, these impressions being made upon both cards by the librarian at the time the book or other article 20 is loaned.

One of these cards also bears the name of the author, the title of the book and the number of the book and is retained by the librarian as a permanent reference record while 25 the other card upon which the borrower's identification character and date of loan of the book has been printed is placed in the pocket of the book to be retained by the borrower as a reminder of the date of expiration 30 of the loan.

It is to be understood that the printing machine will be provided with suitable means for printing the dates of expiration of the time periods of the loan or loans of the same 35 or different books in sequence upon both of the cards beginning from one end of each card.

The main object of the present invention is to provide a separate card for each 40 borrower with distinctive identification type or characters, preferably embossed and arranged upon card in such manner as to permit the card to be placed in the printing machine in such relation to the dating type that when 45 the machine is operated the identification characters and date of expiration of the loan period will be made simultaneously on the reference card and on the borrower's card in opposed relation or alinement.

50 In other words, broadly stated, I have

sought to provide a paper card with a metallic type plate affixed thereto and bearing the borrower's identification character so that the card with the type plate thereon may be used in the printing machine for recording such characters upon another card or cards.

Other objects and uses relating to specific parts of the type-card will be brought out in the following description.

In the drawings:

Figures 1 and 2 are opposite face views of the type-card embodying the features of my invention.

Figures 3 and 4 are enlarged sectional views taken respectively on lines 3—3 and 4—4 Figure 1.

Figure 5 is a perspective view of one end of the type-card, the type plate being removed.

Figure 6 is a face view of the detached type 70 plate.

As illustrated this device comprises a card —1— of relatively stiff paper and a type plate —2— preferably of type metal, the card —1— being preferably rectangular and provided 75 near one of its corners with a rectangular opening —3—, for receiving a portion of the type plate —2—.

The type plate —2— is preferably made of relatively thin sheet metal of about the thickness of the card and comprises a substantially rectangular main body portion —2'— having integral wings or flanges —4— at opposite ends of the opposite longitudinal edges of the main body, said flanges being offset laterally slightly beyond the plane of the main body a distance corresponding approximately to the thickness of the card —1— so that when the main body or rectangular panel —2'— is placed within the opening —3— of the card the flanges —4— will engage in the adjacent face also around the opening to prevent displacement of the type plate through the opposite side of the opening.

The wings or flanges —4— are provided with prongs projecting therefrom through the adjacent portions of the card and clinched against the same to hold the plate against displacement in the other direction.

When the panel —2'— of the plate —2—

is placed within the opening —3— of the card —1— with the flanges —4— resting against one face of the card, the prongs —5— being formed and simultaneously forced through the card and clinched to the other side thereof, by a suitable punch or punches not necessary here to describe for the reason that any suitable means may be employed for affixing the type plate to the card with the panel portion —2'— in the opening —3—.

The rectangular panel —2'— of the type plate —2— is provided with lengthwise rows of borrower's identification characters —6— and —6'— arranged one above the other but in close proximity in parallel relation, those of one row being embossed in one direction to face the corresponding side of the card while those of the other rows are embossed in the opposite direction to face that side of the card.

These raised rows of type forming the identification characters project in opposite directions beyond the planes of the corresponding faces of the card. And although the same characters are used in both rows they are necessarily reversed so that when the card is placed in the printing machine with the type plate between the opposed printing platens and additional cards are placed in the same machine between opposite faces of the type plate and corresponding platens the movement of the platens to their printing positions will cause facsimiles of the corresponding type to be impressed upon the adjacent faces of the additional cards.

It is evident, however, that a single additional card may be placed in the printing machine between the raised faces of either row of type and the adjacent platen to produce a single reproduction of the type upon the additional card.

The primary object, therefore, of this identification card is to permit it to be used in a printing machine for impressing the raised characters of the type plate upon additional cards simultaneously with the impressions made by the dating type of the machine.

The additional cards referred to may be the reference card to be retained in the files of the library, and the borrower's card which is placed in the book loaned to the borrower so that both the librarian and the borrower may have similar records of the identification characters and the due dates for the return of the book or other articles loaned to the borrower. It may be observed that this identification card bearing the type plate is retained by the librarian or borrower for reuse as often as may be required for the particular borrower when borrowing books or other articles to be returned on different dates and in some instances the extra reference card retained by the librarian may be dispensed with in which case the type card —1— will be made of sufficient length to permit the due date

records of borrowed books by the same borrower to be impressed upon the type-card in which case the latter will serve the double purpose of a reference card and as a printing card by simply reversing it end for end in the printing machine.

As previously stated, the type plate —2— is made of thin type metal which when affixed to the card —1— in the manner described has its marginal edges firmly pressed and partially embedded in the paper card so that corresponding faces of the card and plate will be disposed in substantially the same plane to enable the card to be easily inserted into and withdrawn from the printing machine without liability of impairing either the type plate or card.

(a) After the record space on the card —1— has been exhausted by the repeated printing of records thereon, the type-plate —2— may be removed from the card and re-affixed to a new card to be reused to identify the same borrower.

What I claim is:—

1. A device for identifying borrowers of library books comprising a paper card having an opening therethrough, and a thin metal plate affixed to the card and provided with identification characters embossed on both faces thereof in registration with said opening.

2. A device for identifying borrowers of library books comprising a paper card having an opening therethrough, and a thin metal plate affixed to the card and provided with raised identification characters on both faces thereof in registration with said opening.

3. A device for identifying borrowers of library books comprising a paper card having an opening therethrough, and a thin metal plate affixed to the card and provided on each of its opposite faces with a row of identification characters registering with said opening, the type of each row being out of alignment with those of the other row.

In witness whereof I have hereunto set my hand this 10th day of September, 1929.

LLOYD W. MOULTON.
